(57) **CLAIM**

The ornamental design for an upper receiver billet for a firearm, as shown and described.

DESCRIPTION

FIG. 1 is a first perspective view of an upper receiver billet for a firearm according to a first embodiment of the present design;

FIG. 2 is a second rotated perspective view of the design of FIG. 1;

FIG. 3 is a front plan view of the design of FIG. 1;

FIG. 4 is a rear plan view of the design of FIG. 1;

FIG. 5 is a right side view of the design of FIG. 1;

FIG. 6 is a left side view of the design of FIG. 1;

FIG. 7 is top view of the design of FIG. 1;

FIG. 8 is a bottom view of the design of FIG. 1;

FIG. 9 is a first perspective view of an upper receiver billet for a firearm according to a second embodiment of the present design;

FIG. 10 is a second rotated perspective view of the design of FIG. 9;

FIG. 11 is a front plan view of the design of FIG. 9;

FIG. 12 is a rear plan view of the design of FIG. 9;

FIG. 13 is a right side view of the design of FIG. 9;

FIG. 14 is a left side view of the design of FIG. 9;

FIG. 15 is top view of the design of FIG. 9; and,

FIG. 16 is a bottom view of the design of FIG. 9.
